AUXILIARY FUEL TANK FOR VEHICLES

Robert F. Miller, Wimberry Ranch,
Fall Creek, Oreg. 97438

Filed Oct. 13, 1966, Ser. No. 4,263

Term of patent 14 years

(Cl. D14—3)

FIG. 1 is a top plan view of an auxiliary fuel tank for vehicles showing my new design;

FIG. 2 is a side elevation thereof as viewed from the top in FIG. 1;

FIG. 3 is an end elevation as viewed from the right in FIG. 2;

FIG. 4 is a side elevation as viewed from the bottom in FIG. 1;

FIG. 5 is a bottom view as viewed from the bottom in FIG. 2; and

FIG. 6 is an end elevation as viewed from the right in FIG. 1.

I claim:

The ornamental design for an auxiliary fuel tank for vehicles, as shown.
